United States Patent Office.

EDWARD L. WILSON, OF PHILADELPHIA, PENNSYLVANIA.

Letters Patent No. 96,292, dated October 26, 1869.

PHOTOGRAPHERS' REST.

The Schedule referred to in these Letters Patent and making part of the same

To all whom it may concern:

Be it known that I, EDWARD L. WILSON, of Philadelphia, Pennsylvania, have invented certain Improvements on Photographers' Rests; and I do hereby declare the following to be a full, clear, and exact description of the same.

My invention consists—

First, of a certain arrangement of devices, hereafter explained, by which I am enabled to readily move a weighty photographers' rest from one point in a room to another; and

Secondly, of a peculiar method of fastening the rods of the apparatus, so that they can be readily and quickly adjusted to the different positions required, all of which is fully described hereafter.

In order to enable others to make and use my invention, I will now proceed to describe its construction and operation, reference being had to the accompanying drawing, which forms a part of this specification, and in which—

Figure 1 is a side elevation, partly in section of a photographers' rest, with my improvements;

Figure 2, a front view of the same;

Figure 3, a view of part of fig. 1 in a different position;

Figure 4, an inverted plan view of the base of the rest; and

Figures 5 and 6, detached views, drawn to an enlarged scale, and illustrating part of my invention.

Similar letters refer to similar parts throughout the several views.

The base A of the apparatus, the standard B, and the rib a, by which the latter is strengthened, are cast in one piece, forming together a frame of considerable weight.

The base, which is of the peculiar form shown in fig. 4, rests upon three projections or feet b b b, and is recessed on its under side, for the reception of a plate, C, to which, at points adjacent to the feet b, are attached wheels f f f.

The lower end of a vertical rod, H, passes through an opening in the base at the rear of the standard B, and is secured to the plate C, the upper end of this rod being connected by a pin, e, to a lever, I, which is hung to the standard B at a point, e'. (See fig. 1.)

On the upper end of the standard B is a tubular projection, h, adapted to receive a cylindrical rod, J, which can be turned, or raised and lowered to any extent, in the said tubular projection, and secured, after adjustment, by means of a set-screw, i.

An arm, i', which is secured to the upper end of this rod J, supports a second adjustable rod, J', to which the head-rest is attached, the latter being of the usual construction, as seen in figs. 1 and 2.

The method of attaching the back or body-rest L to the vertical rod J forms an important part of my invention, and is as follows:

Two jaws or clamps, M and M', figs. 5 and 6, are ar-

ranged to partly embrace the rod J, and are tightened upon the same by a bolt, p, which is threaded at one end, where it is provided with a thumb-nut, q.

The opposite end of the said bolt is bent, so as to form a hook, p', which passes around a rod, r, to which the rest L is secured, and bears firmly upon and holds this rod against the outside of the clamp M when the thumb-nut q is tightened.

When the above apparatus, which is purposely made of considerable weight, is to be moved from one part of a room to another, the lever I is depressed, it first turning upon the pivot e' until the wheels f touch the floor, and then changing its fulcrum to the pin e, so as to raise the base A clear of the floor, as seen in fig. 3.

When this has been done, the apparatus will run upon the wheels f, and can be readily moved to the desired point, and again permitted to rest steadily upon its feet b when the lever I is released.

When the rest L is to be adjusted, all that is necessary is to loosen the thumb-nut q, which will permit the clamps M and M' to be shifted or turned upon the rod J, and will relieve the pressure of the hook p' upon the rod r, so that the latter can also be moved to any desired position.

This arrangement being entirely under the control of a single nut, enables the position of the body-rest to be quickly changed without the manipulation required in adjusting rests attached in the ordinary manner, and although in attaching the head-rest K but a portion of this device is employed, (the hooked bolt p passing through a permanent block, x,) still the complete arrangement may, if desired, be used or applied to any other portion of the apparatus, which, in adjustment, requires a variety of movements.

I claim as my invention, and desire to secure by Letters Patent—

1. The base A of a photographers' rest, when recessed on its under side for the reception of a movable plate, C, for the purpose specified.

2. The plate C, with its wheels f, contained within the recess of the base A, and so connected to the frame of the apparatus, and operated by a rod, H, and lever I, or their equivalents, that it may be sufficiently depressed to raise the said base, all substantially as and for the purpose herein described.

3. The combination of the bolt p with the clamps M and M', when the latter are adapted for attachment to the rods of a photographers' rest, substantially as and for the purpose set forth.

In testimony whereof, I have signed my name to this specification, in the presence of two subscribing witnesses.

EDWARD L. WILSON.
